by the Secretary of War

Application December 10, 1945, Serial No. 634,099

6 Claims. (Cl. 250—33)

1

This invention relates to radio transmitting and receiving antennas. More particularly it relates to antennas adapted to radiate or receive circularly polarized electrical energy.

The attempts of the prior art to radiate or receive circularly polarized energy have failed for several reasons. Among the most important reasons for this failure was the general failure to radiate the energy from radiators having a rigidly controlled and exact phase difference in the currents flowing in them. The more general failure has been made due to the inability to feed a single coaxial line with energy from a source of single phase power and then to convert this phase power to three single phase power and to transfer the three phase power to the radiators.

It is an object of the present invention to provide an antenna which, when operating as a transmitting antenna, is fed from a single source and radiates circularly polarized energy parallel to its structure and, when operating as a receiving antenna, receives circularly polarized energy parallel to its structure and delivers it through a single transmission line to a receiver.

It is also an object of the present invention to provide an antenna which, when operating as a transmitting antenna, is fed from a single source and radiates circularly polarized energy perpendicular to its structure and, when operating as a receiving antenna, receives circularly polarized energy perpendicular to its structure and delivers it through a single transmission line to a receiver.

It is another object of the present invention to provide a device for converting single phase energy into three phase energy whose adjustability insures 120 degree phase difference of the three phase currents.

It is a further object of the present invention to provide a transmission line for feeding energy between receiving or transmitting apparatus and antennas which are associated in the radiation of circularly polarized energy and in which there is a variable relative phase difference of the three phase currents.

Generally this invention comprises a coaxial line fed by single phase energy with a tapered section having a constant impedance everywhere along its length. Two conductors of adjustable impedance are attached to the inner conductor of the tapered section of the coaxial line at its larger end and feed energy to two of the radiators. The outer conductor of the coaxial line is connected to a third radiator. The currents in each of these radiators is 120 degrees out of phase with the current in either of the others.

Other objects, features, and advantages of this invention will suggest themselves to those skilled in the art and will become apparent from the following description of the invention taken in con-

2

nexion with the accompanying drawings in which:

Fig. 1 is a diagrammatic sketch showing the equivalent electrical circuit employed in antennas constructed in accordance with the principles of this invention;

Fig. 2 is a cross-sectional view of an antenna structure embodying the principles of this invention which radiates circularly polarized energy parallel to the axis of the antenna structure;

Fig. 3 is an end view of the antenna structure of Fig. 2 showing the location of the radiators;

Fig. 4 is a cross-sectional view of an antenna structure embodying the principles of the present invention which radiates circularly polarized energy perpendicular to the axis of the antenna structure; and

Fig. 5 is an end view of the antenna structure of Fig. 4 showing the radiators.

For simplicity of description the case of a transmitting antenna is discussed in this specification but it is to be understood that the electrical and other principles apply with equal force to a receiving antenna.

Referring more particularly to Fig. 1 the circuit employed in the antennas of this invention for converting single phase energy into three phase energy and vice versa is generally designated by 10. Single phase energy is fed into the terminals 11, 11. From terminals 11, 11 the energy is divided into three distinct paths or circuits denoted by 12, 13, and 14 which are connected to radiators 15, 16, and 17 respectively. Resistor 18 is connected between circuits 12 and 13, capacitance 19 is in circuit 13, and inductance 20 is in circuit 14.

It is obvious from the fundamental functions of the resistance 18, capacitance 19, and inductance 20 that the current relationships in circuit 10 are as follows: the current in circuit 12 is in phase with its voltage, the current in circuit 13 leads the current in circuit 12 by 120 degrees, and the current in circuit 14 lags the current in circuit 12 by 120 degrees.

Referring to Figs. 2 and 3 the radiators and the housing are generally designated by 30. The coaxial line 31 is fed from a single phase source of energy. A tapered section 32 is joined to coaxial line 31 at 33 and to the antenna supporting structure 30 at 35. The taper of section 32 and the relative diameters of the inner and outer conductor in that section are such that its characteristic impedance remains unchanged throughout its entire length. Inner conductor 36 of tapered section 32 is joined to conductors 37 and 38 connected to radiators 39 and 40 respectively. Outer conductor 34 of this tapered section is connected to outer wall 41 of housing 30 which acts as a continuation of the outer con-

ductor beyond tapered section 32 and is connected to radiator 42.

Conductors 37 and 38 are secured to conductor 36 by any suitable means such as screw joints 43 and 44. At their other ends conductors 37 and 38 are provided with internally threaded portions 45 and 46 respectively into which screws 47 and 48 fit. Plungers 49 and 50 are attached to screws 47 and 48 respectively and are held in place against any lateral displacement by fingers 51 and 52 or by any other suitable means.

Plungers 49 and 50 fit respectively into longitudinal openings 53 and 54 in conductors 37 and 38. They extend into these openings substantially one quarter wavelength corresponding to the central frequency of the operating range.

Plunger 48 is in contact with the inner circumference of section 53 thereby producing a shorted one quarter wavelength section which, as is well known, possesses inductive characteristics. This is the inductance 29 of the equivalent circuit shown in Fig. 1. Plunger 50 is not in contact with the inner circumference of section 54, therefore it follows that section 54 is an open circuited one quarter wavelength line and possesses capacitive characteristics. This is the capacitance 19 of the equivalent circuit shown in Fig. 1.

Screws 47 and 48 may be manually positioned in threaded sections 45 and 46 to move plungers 49 and 50 thereby adjusting the effective electrical length of sections 53 and 54. To change the optimum operating frequency these plungers are moved so that sections 53 and 54 remain one quarter wavelength, as shown, so that the currents in conductors 37 and 38 are 120 degrees out of phase with each other. Changes in the relative positions of plungers 49 and 50 will change this phase relationship. Conductors 37 and 38 are permanently secured within housing 30 in the position shown by the cylindrical dielectric supports 55 and 56.

A "folded" section 57 is attached outside of housing 30 to outer conductor 41. In this embodiment it is electrically connected at its end remote from the radiators and, therefore, acts as a choke to prevent conductor 41 itself from acting as a radiator.

The radiators 39, 40, and 42 are physically positioned 120 degrees apart at the end of housing 30 and perpendicular to its longitudinal axis and radiate energy in a forward direction parallel to the axis of the housing 30.

When it is desired to radiate energy in a direction perpendicular to the axis of housing 30, the same structure may be used with the modification of a few details which may be understood by referring to Figs. 4 and 5. Coaxial line 31, tapered section 32, and conductors 37 and 38 and their associated parts such as plungers 49 and 50 are similar to the corresponding parts in the embodiment just described. In this embodiment, however, outer conductor 61 of housing 30, instead of being connected directly to one of the radiators as in the previously described embodiment, is terminated along a plane perpendicular to the longitudinal axes of conductors 37 and 38 a distance away from radiators 62 and 63 which are connected solely to conductors 37 and 38 respectively. These radiators instead of being perpendicular to the longitudinal axis of their respective conductor make an angle of 30 degrees with it. A cylindrical element 64 is, in this embodiment, electrically connected to the radiator end of conductor 61 and folded back parallel to that conductor so that it serves as the third

radiator. The radiated energy from radiators 62, 63 and 64 combine to produce circularly polarized radiation which is perpendicular to the axis of housing 30.

It is seen from the above description of the present invention that the antennas described have wide application and usefulness and that considerable utility may be added to apparatus by associating with it either or both embodiments described.

While there has been here described what is at present considered to be the preferred embodiment of the invention, it will be obvious to those skilled in the art that various changes and modifications may be made therein without departing from the scope of the invention.

What is claimed is:

1. In an antenna system for propagating perpendicular to said antenna structure circularly polarized waves, a coaxial transmission line, three radiating elements, the first of said radiating elements being a folded one-quarter wavelength section of the outer conductor of said transmission line, the second of said radiating elements being connected to the inner conductor of said transmission line through a capacitance, and the third of said radiating elements being connected to the inner conductor of said transmission line through an inductance, and means for adjusting said capacitance and inductance whereby the phase relationship between the currents in said radiating elements may be adjusted.

2. In an antenna system for propagating perpendicular to said antenna structure circularly polarized waves, a coaxial transmission line, three radiating elements, the first of said radiating elements being a folded one-quarter wavelength section of the outer conductor of said transmission line, the second of said radiating elements being connected to the inner conductor of said transmission line through a capacitance, and the third of said radiating elements being connected to the inner conductor of said transmission line through an inductance, and means for adjusting said capacitance and inductance whereby the optimum frequency of said system may be altered.

3. In an antenna system for propagating perpendicular to said antenna structure circularly polarized waves, a coaxial transmission line, three radiating elements, the first of said radiating elements being a folded one-quarter wavelength section of the outer conductor of said transmission line, the second of said radiating elements being connected to the inner conductor of said transmission line through a capacitance, and the third of said radiating elements being connected to the inner conductor of said transmission line through an inductance, the values of said inductance and said capacitance being such that the currents in said radiating elements are separated from each other by 120 degrees.

4. An antenna for radiating circularly polarized waves comprising a tapered coaxial transmission line, means for connecting the smaller end of said transmission line to a source of electromagnetic energy, first, second and third energy radiating elements having coplanar axes, a conductive sleeve for connecting said first radiating element to the larger end of the outer conductor of said coaxial line, first and second parallel conductors disposed within said sleeve for connecting said second and third radiating elements to diametrically opposite points on the larger end of the inner conductor of said coaxial line, said first and second conductors comprising variable

impedance means for varying the phase of energy supplied to said second and third radiating elements.

5. An antenna for radiating circularly polarized waves comprising a tapered coaxial transmission line, means for connecting the smaller end of said transmission line to a source of electromagnetic energy, first, second and third radiating elements having coplanar axes, said elements being so arranged that the axes of said three elements meet at a common point, a conductive sleeve for connecting said first radiating element to the larger end of the outer conductor of said coaxial line, first and second parallel conductors disposed within said sleeve and parallel to the axis thereof for connecting said second and third radiating elements to diametrically opposite points on the larger end of the inner conductor of said coaxial line, said first and second conductors each comprising first and second conductive elements, variable capacitive means joining said first and second conductive elements of said first conductor, and variable inductive means joining said first and second conductive elements of said first conductor.

6. An antenna for radiating circularly polarized waves comprising a tapered coaxial transmission line, means for connecting the smaller end of said transmission line to a source of electromagnetic energy, first, second, and third radiating elements having coplanar axes arranged so that the axes of said three elements meet at a common point at angles of substantially 120 degrees, a conductive sleeve for connecting said
